PADLOCK

Joseph Allman, Chicago, Ill., assignor, by mesne assignments, to Joseph Allman, trustee

Application June 27, 1935, Serial No. 28,638
Renewed June 13, 1938

11 Claims. (Cl. 70—25)

The present invention relates to padlocks, and is particularly concerned with the provision of an improved padlock of the permutation type, adapted to be actuated by manual actuating devices, which may be actuated without necessity for looking at any dial so that the lock may be opened in the dark as well as the light.

One of the objects of the invention is the provision of an improved permutation padlock in which there are no parts exposed that can be drilled or otherwise attacked with ordinary tools to break the lock.

Another object of the invention is the provision of an improved permutation padlock in which there are no parts which can be damaged in such manner as to open the lock by means of a hammer.

Another object of the invention is the provision of an improved permutation lock adapted to be actuated by push buttons, in which the parts are so formed that they cannot be grasped by a pair of pliers or other gripping tools to push or pry the push buttons out of the lock.

Another object of the invention is the provision of an improved permutation padlock structure which is simple, efficient, sturdy and capable of manufacture at such a low cost that it may be manufactured within the means of a vast number of purchasers.

Other objects and advantages of the invention will be apparent from the following description and the accompanying drawings, in which similar characters of reference indicate similar parts throughout the several views.

Referring to the drawings, of which there are two sheets,

Fig. 1 is a side elevational view of the padlock;

Fig. 2 is an elevational view of the padlock mechanism, with one of the cover plates removed;

Fig. 3 is a vertical sectional view taken on the plane of the line 3—3 of Fig. 4;

Fig. 4 is a sectional view taken on the plane of the line 4—4 of Fig. 3, looking in the direction of the arrows;

Fig. 5 is a sectional view, taken on the plane of the line 5—5 of Fig. 1;

Fig. 6 is a bottom plan view;

Fig. 7 is a sectional view taken on the plane of the line 7—7 of Fig. 3, looking in the direction of the arrows;

Fig. 8 is a sectional view taken on the plane of the line 8—8 of Fig. 3, looking in the direction of the arrows;

Fig. 9 is a fragmentary sectional view taken on the plane of the line 9—9 of Fig. 2, looking in the direction of the arrows;

Fig. 10 is a sectional view of the lock, showing the end elevation of the ratchet member;

Fig. 11 is a sectional view, showing the cam in elevation;

Fig. 12 is another sectional view, showing one of the permutation members in elevation; and

Fig. 13 is a sectional view, showing another of the permutation members in elevation.

Referring to Figs. 1 to 4, 20 indicates in its entirety the padlock, which is preferably provided with a body 21, which may be constructed of a block of hardened metal suitable for resisting the attacks of ordinary tools.

The block 21 has a plurality of flat, rectangular sides, the corners 22 being preferably chamfered, but the block may be made in any desired shape. It is provided with an enlarged circular transverse bore 23 for the purpose of housing the mechanism of the lock, and with a pair of 15 inwardly extending bores 24, 25 at the top, which latter bores are parallel to each other and communicate with the enlarged bore 23.

It also has a pair of parallel cylindrical bores 26, 27 extending inwardly from the bottom for 20 the purpose of housing the push buttons 28, 29, and these latter bores also communicate with the enlarged bore 23.

The padlock is preferably provided with a U-shaped shackle 30, comprising a hardened metal 25 rod bent to substantially U shape and having a pair of parallel legs 31, 32, the latter leg being longer, since it is adapted to be rotatably and slidably mounted in the lock body.

The leg 31 is provided at its lower end with a 30 transverse groove, having a diagonal surface 33 and a transverse shoulder 34, the latter being adapted to engage a locking bolt or pivoted member when the padlock is in locked condition. The opposite leg 32 is also preferably provided with 35 a similar beveled surface 33 and a shoulder 34, the two grooves facing each other.

In some embodiments of the invention, however, only one pivoted locking member may be utilized. Each of the legs 31, 32 is preferably slidably 40 mounted in a hardened metal sleeve 35 or 39, which has a lower reduced cylindrical portion 36 that has a pressed frictional fit in the bore 25. The sleeve is driven home against the annular shoulder 37 and has its edge at one side removed 45 at the point 38, so that the sleeve will not interfere with the operation of the other parts of the mechanism. In other words, the sleeve 35 does not project into the enlarged bore 23.

The sleeve 35 is cut away at 56, at the upper 50 end, so that the shackle 30 may be pivoted to move the leg 31 out of the sleeve 35 when the groove 44 registers with pin 41. The upper part of sleeve 35 thus serves to align the leg 31, with the bore in the sleeve 35, when rotating the shackle 30 back 55 into the dotted line position shown in Fig. 1.

The bore 24 is also provided with a similar sleeve 39, the latter sleeve being also provided with an aperture 40 for passing a pin 41, which has a drive fit in a transverse bore 42. The leg 32 is provided 60

with a vertically extending slot 43 on the side towards the pin 41, so that the pin 41 may slide in the slot 43, preventing rotation of the shackle 30 until it reaches the upper limit of its movement, where the slot 41 extends sidewise at 44, on the periphery of the leg 32.

The leg 32 is also provided with an axially extending bore 45 in its lower end for receiving the compression spring 46, which tends to move the shackle 30 up out of the padlock body. The mechanism of the padlock is supported upon a cylindrical metal supporting member 47, which also has a bore 48 for the leg 32, the bore 48 registering with the bore in the sleeve 39 when the parts are assembled. Bore 48 may be provided with a plate 49 at its lower end, which is pressed in place to provide a better seat for the spring 46.

The body, at each end of the enlarged bore 23, is preferably provided with counterbores 50, 51, substantially fitting the outer edges 52 of the beveled cover plates 53, 54. After all the parts of the lock are assembled, the adjacent part of the lock body 21 may be spun over the beveled edges of the cover plates 53, 54 to permanently secure these plates to the body.

One of the cover plates, such as 53, for example, is preferably provided with some identifying mark to distinguish it from the other cover plate, so that the operator may tell in the dark which 30 is the front side of the lock, for the purpose of identifying the two push buttons from each other, as a right push button and a left push button. In the present embodiment an ornamental circular groove 55 is formed in the front cover plate for 35 this purpose.

Referring to Figs. 2, 4, 7 and 8, the mechanism of the lock is mounted upon the circular body 47. This body is provided with a transverse cylindrical bore 57 for receiving the permutation discs. 40 It also has the upwardly extending bores 58, 59, which register with the bores 26, 27, respectively, when the lock is assembled, and these latter bores communicate with the centrally located bore 57. The supporting member 47 is also provided with a circular bore 60, centrally located therein with respect to the periphery of the body 47 for passing the shaft 61, which has a reduced knurled end 62 that may have a drive fit in a bore 63 in the back cover plate 54. Shaft 61 is thereby prevented from rotating, and it rotatably supports the permutation discs 64, 65, the cam disc 66, and the ratchet wheel 67.

The tumbler discs 64, 65 are spaced from each other by a washer 68 which is provided with a radially inwardly extending key 69, adapted to extend into the key-way 70 in the shaft 61. A similar washer 71 is mounted between the tumbler disc 65 and the cam 66. Cam 66 may be fixedly secured to the ratchet wheel 67 by being pressed on 60 a tubular hub 72 carried by the ratchet wheel. The washers 68, 71 isolate the permutation discs from each other so that they can be rotated only by the inter-engagement of the pins carried thereby.

65 The permutation discs 64, 65 both have slots 73, 74 which are adapted to receive the locking lug 75 when these slots are aligned. The cam 66 has its periphery arranged on an increasing radius so that at its largest radius the cam surface 76 is adapted to lift the locking lug 75 out of the slots 73, 74. The smallest radius portion of the cam 66 permits the locking lug 75 to drop into the slots 73, 74, if they are aligned. The permutation disc 64 may be provided with another slot or cut-away 70 portion 77, forming the radial shoulders 78, 79 on

each side of a stop pin 80. Stop pin 80 is mounted with a pressed fit in a suitable bore 81 in the body 47. The purpose of the shoulders 78, 79 is to limit the rotation of the first permutation disc so that it will not take so many step-by-step impulses to move it back to its initial position. Therefore, the first number of the combination may be much smaller than it would need to be if stops 78-80 were absent.

Permutation disc 64 is also provided with a laterally projecting pin 82, which projects past the washer 68 into position to engage a pin 83, which projects from both sides of the permutation disc 65. The cam 66 also has a laterally projecting pin 84, which projects into the path of the left end of pin 83 past the washer 71. The inter-engagement of these pins serves to permit the alignment of the slots 73, 74 in the permutation discs by actuating the ratchet wheel 67.

Ratchet wheel 67 comprises a substantially cylindrical metal member provided with a plurality of equally spaced slots 85 and teeth 86 on its periphery. It has an enlarged bore 87 from which extends a bore 88 of the hub 72, so that the ratchet wheel may be rotatably mounted on the shaft 61, and a spring 89 may be mounted in the bore 87. Shaft 61 is provided with a threaded and countersunk bore 90 for receiving the screw 91, which passes through and secures a plate 92 in the counterbore 87 to provide a seat for the spring 89. The spring 89 constantly urges the assembly of rotatably mounted parts on the shaft 61 axially into engagement with each other and maintains these parts under predetermined pressure, so that the friction between them is sufficient to hold the tumbler discs in the position to which they are turned by the operation of the pins 82-84.

The locking lug 75 is carried by the lower end of a sliding member 93, which is slidably mounted in the body 47. The sliding member 93 is provided with a pair of laterally projecting lugs 94, 95, and it is slidably mounted in a guideway 96 in the body 47. The body 47 is also provided with slots 97, 98, which communicate with the guideway 96 so that pivoted locking bolts 99, 100 may be mounted in the slots 97, 98, an arm of each locking bolt projecting into the guideway 96. Each of the locking bolts may be identical in construction, and therefore only one need be described. They are rotatively mounted on pins 101 and are provided with the partially cylindrical actuating arm 102 and with the other arm having a laterally projecting locking shoulder 103.

The slider 93 is provided with an axially extending bore 104, within which is housed a compression spring 105. Compression spring 105 engages the upper wall of the enlarged bore 23 and urges the slider 93 downward, or in such a way as to tend to withdraw the locking bolts 99, 100. They cannot be withdrawn, however, unless the slots 73, 74 of the permutation discs are aligned. The laterally projecting lugs 94, 95 have inwardly extending slots 106, 107, within which are mounted the partially cylindrical ends of the arms 102 of the locking bolts 99, 100. The guideway 96 communicates with the centrally located bore 57, so that the locking lug 75 may pass downward into the slots 73, 74.

The ratchet wheel 67 is adapted to be actuated by the push buttons 28, 29. For this purpose there is mounted in each of the bores 58, 59 a plunger 108, which is provided with a head 109, slidably mounted in the bore 58. The reduced 75

cylindrical stem 110 of the plunger 108 is slidably mounted in a complementary bore 111, and a spring 112 engages a portion of the body 47 and constantly urges the plunger 108 downward into engagement with the inner end of a sleeve 113. Each of the plungers 108 carries an auxiliary stem 19 and a pawl 114, pivotally mounted thereon by means of a pin 115.

The body 47 is suitably cut away and provided with a slot so that the pawl 114 may move up and down with the plunger 108. Pawl 114 is provided with a ratchet-engaging shoulder 116 and a beveled surface 117, and the end of the pawl has a socket 118 for receiving the end of a spiral spring 119, the other end of the spring being fixedly secured to the body 47 by being mounted in a bore in a screw 162. Spring 119 constantly urges the pawl 114 toward the ratchet wheel, but the edge of the slot 111 limits the movement of the pawl 114 and prevents it from engaging the ratchet wheel except during a predetermined range of the motion of the plunger 108.

As plunger 108 is moved upward, the pawl is moved over into engagement with the ratchet wheel 67, where it engages in one of the slots and moves the ratchet wheel a movement which corresponds to the space corresponding to one slot and one tooth.

Both of the pawls being identical in structure, only one will be described, but the one pawl is adapted to move the ratchet wheel step by step in a clockwise direction, and the other in a counter-clockwise direction, corresponding to the usual movements of the dial of a permutation lock.

The push buttons 28, 29 comprise hardened metal members provided with frusto-conical outer portions 121. These frusto-conical portions are so hardened that no impression can be made thereon by any ordinary tool, and they cannot be gripped by pliers or other clamping members so as to withdraw them from the lock. The push buttons also have a cylindrical body portion 122, which may be slidably mounted in the cylindrical bore of the sleeve 113.

Each push button preferably has an inner axial bore 124 for receiving the safety spring 125, which is housed in the push button and extends into engagement with the head 109 of plunger 108. This spring is preferably stronger than the spring 112 so that when the push buttons are actuated under ordinary conditions spring 125 does not give but is sufficient to transmit the motion of the push button 28 to the plunger 108.

Sleeve 113 is also made of hardened metal, and has a pressed fit in the bore 26. It has an inwardly extending annular flange 126 at its inner end, providing a seat for the head 109 of plunger 108. At its outer end it has an outwardly extending annular shoulder 127, determining the final position of the sleeve in its bore.

The push button has a reduced cylindrical portion, providing space for a metal ring 128, which has a pressed fit in the bore 123, providing a stop shoulder for the outward movement of the push button and holding the push button in its socket. The purpose of the spring 125 is to protect the other parts of the mechanism from hammer blows on the push buttons 28, 29. Whenever such blows are given the push buttons, the spring 125 gives and absorbs and cushions the blow that would otherwise be transmitted to the other mechanism of the lock.

The operation of the lock is as follows: The 75 push buttons 28, 29 are pushed a predetermined

number of times in predetermined sequence, depending upon the combination, to align the permutation discs. When they are aligned, the lug 75 passes into the slots of the discs, and the locking bolts 99, 100 are withdrawn. Spring 46 then causes the locking member 30 to project from the padlock. The padlock may only be locked when the permutation discs and/or cam are so arranged as to project the locking member 75 from the slots. The lock may be locked with a few turns 10 by merely actuating the cam with one of the buttons so as to project the locking lug 75 from the slots, thereby actuating the locking bolts 99, 100. Under such conditions, it is only partially locked, and may be brought back to the initial 15 position by pushing the other push button to move the cam backward as many steps as were taken to lock the device. Of course, it may be securely and thoroughly locked by following a suitable combination, and to anyone not familiar 20 with the device it is just as well locked when in the partially locked condition I have just mentioned.

The present device is adapted to withstand the attacks of all ordinary tools, and is practically 25 burglar-proof. It can be unlocked in the dark as well as in the light by actuating the push buttons, since it is not necessary to look at the push buttons while giving them a predetermined number of pushes in proper sequence.

While I have illustrated and described a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In a permutation lock, the combination of a support with a plurality of permutation discs, a ratchet wheel for actuating said permutation discs step by step, a locking member controlled by said permutation discs, a pawl, a manual actuating member for actuating said ratchet wheel, and resilient means between said pawl and said manual actuating member adapted to give when a blow is struck upon said manual actuating member to protect the mechanism of the lock from 45 hammer blows.

2. In a permutation lock, the combination of a support with a plurality of permutation discs, a ratchet wheel for actuating said permutation discs step by step, a locking member controlled 55 by said permutation discs, a pawl, a manual actuating member for actuating said ratchet wheel, resilient means between said pawl and said manual actuating member adapted to give when a blow is struck upon said manual actuating member to protect the mechanism of the lock from 60 hammer blows, said manual actuating member comprising a push button, and spring means for urging said push button outwardly from said support.

3. In a permutation lock, the combination of a support with a plurality of permutation discs, a ratchet wheel for actuating said permutation discs step by step, a locking member controlled by said permutation discs, a pawl, a manual actuating member for actuating said ratchet wheel, resilient means between said pawl and said manual actuating member adapted to give when a blow is struck upon said manual actuating member to protect the mechanism of the lock from 70 75

- hammer blows, said manual actuating member comprising a push button, and spring means for urging said push button outwardly from said support, said push button and support being constructed of material adapted to withstand the attacks of ordinary tools, and said push button having a surface tapering toward the outer end to prevent application of a pulling force by a clamping tool.
10. 4. In a permutation padlock, the combination of a metal body, all exposed parts of which are armored, with a permutation lock in said body, a pair of push buttons for actuating said lock, said push buttons projecting from said body, and 15 said push buttons being constructed with formations having a surface tapering toward the outer end, whereby the push buttons cannot be gripped by a clamping tool to withdraw them.
5. In a padlock, the combination of a metal body formed with an enlarged transverse circular bore, a permutation locking mechanism located in said bore, actuating push buttons located in bores transversely to said enlarged bore for actuating said lock, a U-shaped shackle having its legs extending into other bores located transversely to said enlarged bore, said enlarged bore being closed on each side by a hardened metal plate located in said enlarged bore, and the material of said body being spun over said 30 metal plates, one of said plates having a distinguishing mark by means of which the operator may distinguish the front of the lock and distinguish the push buttons as right and left push buttons, so that the lock may be actuated 35 in the dark.
6. In a permutation padlock, the combination of a supporting body provided with a transverse circular bore, a U-shaped shackle having both of its ends slidably mounted in bores which 40 communicate with said transverse bore, spring means for projecting said shackle, one of the legs of said shackle being longer, stop means for retaining said latter leg in said body, guide means for permitting rotation of said latter leg, 45 permutation locking means in said body for locking said shackle with both legs in said body, and a pair of push buttons slidably mounted in said body and adapted to actuate said permutation locking means, and said push buttons having a 50 surface tapering toward the outer end, whereby they cannot be gripped by any ordinary clamping tool to withdraw the push buttons.
7. A locking unit for padlocks comprising a substantially cylindrical body provided with a 55 cylindrical transverse bore for receiving the permutation discs, a shaft fixedly mounted in said bore, a plurality of permutation discs on said shaft, fixed bearing means between said discs for preventing one permutation disc from entraining another except through the interconnecting shoulders carried thereby, a pair of pivoted locking bolts, a movable member carrying a locking lug and mechanically connected to said locking bolts, said permutation discs having slots adapted 60 to be aligned to receive said locking lug and permit the movement of said locking bolts.
8. A locking unit for padlocks, comprising a substantially cylindrical body provided with a cylindrical transverse bore for receiving the 65 permutation discs, a shaft fixedly mounted in said bore, a plurality of permutation discs on said shaft, fixed bearing means between said discs for preventing one permutation disc from entraining another except through the interconnecting shoulders carried thereby, a pair of pivoted locking 70 bolts having a surface tapering toward the outer end, whereby they cannot be gripped by ordinary gripping tools to remove the push buttons.

ing bolts, a movable member carrying a locking lug and mechanically connected to said locking bolts, said permutation discs having slots adapted to be aligned to receive said locking lug and permit the movement of said locking bolts, resilient means for urging said locking lug into said slots of said permutation discs, and cam means adapted upon rotation to force said locking lug out of said slots to effect a locking movement of said locking bolts.

9. In a permutation padlock, the combination of a supporting body provided with an enlarged transverse bore, said body also having a pair of inwardly extending bores at the top, and a pair of inwardly extending bores at the bottom, communicating with said enlarged bore, a U-shaped shackle having its legs slidably mounted in said top bores, one of said legs being longer and adapted to permit rotation of said shackle when said other leg is out of its top bore, a permutation locking device mounted in said enlarged bore, and comprising a pair of locking bolts adapted to engage shoulders on said legs, and a pair of push buttons in said lower bores adapted to actuate said permutation locking means by a predetermined number of impulses in predetermined sequence.

10. In a permutation padlock, the combination of a supporting body provided with an enlarged transverse bore, said body also having a pair of inwardly extending bores at the top, a pair of inwardly extending bores at the bottom, communicating with said enlarged bore, a U-shaped shackle having its legs slidably mounted in said top bores, one of said legs being longer and adapted to permit rotation of said shackle when said other leg is out of its top bore, a permutation locking device mounted in said enlarged bore, comprising a pair of locking bolts adapted to engage shoulders on said legs, and a pair of push buttons in said lower bores adapted to actuate said permutation locking means by a predetermined number of impulses in predetermined sequence, and spring means interposed between said push buttons and the mechanism of said 40 permutation locking means to absorb hammer blows and protect said mechanism from hammer blows on said push buttons.

11. In a permutation padlock, the combination of a supporting body provided with an enlarged transverse bore, said body also having a pair of inwardly extending bores at the top, a pair of inwardly extending bores at the bottom, communicating with said enlarged bore, a U-shaped shackle having its legs slidably mounted in said top bores, one of said legs being longer and adapted to permit rotation of said shackle when said other leg is out of its top bore, a permutation locking device mounted in said enlarged bore, comprising a pair of locking bolts adapted to engage shoulders on said legs, a pair of push buttons in said lower bores adapted to actuate said permutation locking means by a predetermined number of impulses in predetermined sequence, and spring means interposed between said push buttons and the mechanism of said permutation locking means to absorb hammer blows and protect said mechanism from hammer blows on said push buttons, said push buttons having a surface tapering toward the outer end, whereby they cannot be gripped by ordinary gripping tools to remove the push buttons.
